Primary Examiner—Lucy Lieberman

[57] CLAIM

The ornamental design for a plastic container, as shown and described.

DESCRIPTION

FIG. 1 is a top front perspective view of a plastic container showing my new design;

FIG. 2 is a front elevation on an enlarged scale, the rear elevation is the same except for the threading on the neck; FIG. 3 is a right side elevation, the left side elevation is the same except for the screw threading on the neck;

FIG. 4 is a top plan view;

FIG. 5 is a sectional view taken along line 5—5 in FIG. 2; FIG. 6 is a front elevation of a second embodiment of the plastic container;

FIG. 7 is a view taken from the right in FIG. 6;

FIG. 8 is a sectional view taken along the line 8—8 in FIG. 6; and,

FIG. 9 is a front elevation of a third embodiment of the plastic container.

The portions of the three embodiments that are not shown in the drawings do not form part of the claimed design.
